UNITED STATES PATENT OFFICE.

HENRY MEIER, OF NEW YORK, N. Y.

DESIGN FOR A NIPPLE.

SPECIFICATION forming part of Design No. 27,241, dated June 22, 1897.

Application filed May 8, 1897. Serial No. 635,739. Term of patent 14 years.

To all whom it may concern:

Be it known that I, HENRY MEIER, a citizen of the United States, residing in the city, county, and State of New York, have invented and produced a new and original Design for a Nipple, of which the following is a specification.

The leading feature of my design is a nipple substantially as shown in the accompanying drawing, which illustrates a nipple embodying my design.

In the drawing the nipple is shown as comprising a bulbous stem *a*, from which a neck *b* extends, which terminates in a laterally-disposed flange or rib *c*.

What I claim is—

The design for a nipple, substantially as shown.

HENRY MEIER.
